(57) **CLAIM**

I claim the ornamental design for a retainer device, as shown and described.

DESCRIPTION

FIG. 1 is an exploded front perspective view of a retainer device showing my new design;

FIG. 2 is an unexploded front perspective view;

FIG. 3 is an exploded back perspective view;

FIG. 4 is an unexploded back perspective view;

FIG. 5 is a front plan view;

FIG. 6 is a back plan view;

FIG. 7 is a side plan view;

FIG. 8 is a side plan view opposing the side depicted in FIG. 7;

FIG. 9 is an end plan view, shown without the broken line attachment fitting; and,

FIG. 10 is an end plan view of the side opposing the side depicted in FIG. 9, also shown without the broken line attachment fitting.

The broken lines in the drawings are environmental lines, which do not form part of the claimed design.

1 Claim, 3 Drawing Sheets
